Specification of Letters Patent.

Patented Feb. 8, 1916.

Application filed August 9, 1913. Serial No. 783,866.

To all whom it may concern:

Be it known that I, CHARLES A. MORRIS, a citizen of the United States, residing at Montclair, county of Essex, and State of New Jersey, have invented a certain new and useful Excavating Apparatus, of which the following is a specification.

This invention is an excavating apparatus, the same pertaining to a digging bucket 10 of the sectional type, such as are known as the "clam shell" bucket or "orange peel" bucket, although the invention may be embodied in a grapple for hoisting and conveying rocks, boulders, etc.

15 Prior to this invention, sectional buckets or analogous structures have been constructed with means operable by the cable or cables for opening and closing the bucket so as to render it self-loading when in contact with the material, and to render it self-dumping after the material shall have been hoisted and conveyed to the desired point of deposit. Many of the prior structures have embodied toggle mechanism for 20 effecting the opening and closing movement of the pivoted sections composing the structure, but in nearly all instances such toggle mechanism was constructed and operated in a manner to involve a loss of force 25 and efficiency in the movement of said pivoted members as the latter move toward their closed positions, the force and efficiency decreasing progressively the more the sections travel toward their closed positions. As the material is loaded into the 30 bucket by the operation of closing the pivoted sections, it is desirable, and in fact necessary, to increase the force of the toggle mechanism during the closing period 35 of the sections, for the reason that the resistance of the material increases during the closing period of the sections. Accordingly, the present invention embodies a sectional bucket or analogous structure of the class 40 specified embodying members each pivoted intermediate the ends thereof to a substantially rigid framework when combined with a toggle mechanism the parts of which are so organized and connected as to apply force 45 increasingly to the pivoted members as the latter approach the closed positions thereof. The principle of the invention is the same

whether the invention is embodied in a grapple, a clam shell bucket, or an orange peel bucket.

55 An important structural advantage secured by my invention is that the height, or vertical dimensions, of the grapple or bucket is substantially less than that of prior buckets, without involving any decrease in the capacity of the bucket. The height of the head or frame is less than the corresponding part in prior structures owing to the simple and compact arrangement of the toggle mechanism.

60 65 Other features of the invention and the advantages thereof will appear from the following detail description.

70 In the drawings, Figure 1 is a side elevation of a grapple embodying this invention with the parts in their open or spread positions. Fig. 2 is a vertical section on the line 2—2 of Fig. 3, looking in the direction of the arrow, illustrating the parts in their closed positions. Fig. 3 is a sectional plan 75 view on the line 3—3 of Fig. 1. Fig. 4 is a plan view of the parts at the upper end of the grapple, said figure being on a reduced scale as compared with Figs. 1, 2 and 3. Fig. 5 is a detail section on the line 80 5—5 of Fig. 3. Fig. 6 is a side elevation of the invention as embodied in a clam shell bucket. Fig. 7 is a vertical section on the line 7—7 of Fig. 8 looking in the direction 85 of the arrow. Fig. 8 is a section in a plane 85 at right angles to Fig. 7 and on the dotted line 8—8 of said Fig. 7 looking in the direction of the arrow. Fig. 9 is a detail view of one member composing the head or frame, and the slide employed in connection with said member.

90 I will first proceed to describe the invention embodied in a grapple, substantially as shown in Figs. 1 to 5, inclusive, wherein A designates the pivoted members, B a head or skeleton frame, C a vertically movable member or carrier constituting one element of the toggle mechanism, D the links of said toggle mechanism, E a hoist line, and F a dump line.

95 100 Any desired number of members A may be used, but the drawings show four members arranged on the quarters of a circle, said members being movable radially from

the center of a circle. Each member is shown as consisting of side plates a a' and cross stays a' attached rigidly to the side plate so as to unite them in a substantial manner. The member is pivoted intermediate its ends in one part of the frame or head B by a bolt f , and at the free end of member A there is provided a digging toe f' . The side plates of member A are curved longitudinally so as to give the member the required form. At the upper end of two members A are mounted pulleys g , which are adapted to be engaged by the dump line F in the manner hereinafter described.

15 The head or skeleton frame B is shown as consisting of a series of upright inclined channel pieces b , a second series of upright channel pieces b' , transverse bottom pieces b^2 , and a top piece b^3 . The top and bottom pieces b^2 b^3 , respectively, are parallel, and to said pieces are firmly riveted or bolted the upper and lower ends of the inclined and inside rails b b' , thereby producing a substantial frame adapted to carry or support the several moving parts of the structure. As shown more particularly in Fig. 3, each member A is positioned between the inclined pieces b and the lower pieces b^2 of the frame, and through the several parts 20 25 30 pass the bolts f so as to pivotally connect each swinging member A to the head or frame in a substantial manner.

The movable part or carrier C is positioned between the inside members b' so as 35 to slide freely in an up and down direction between said members. This vertically movable part or carrier is shown as consisting of side plates c united by cross bolts or studs c' , said side plates c having any 40 suitable form, preferably the form shown more particularly in Fig. 2. The side plates are provided with suitable bearings for a shaft or arbor h of a pulley H, the latter being positioned partly between the side 45 plates c of the carrier so that the pulley is movable with said carrier up and down within the frame B.

The movable part or carrier C forms one 50 element of the toggle mechanism, the other elements of which consist of links D. The links correspond in number to pivoted members A, and they are arranged radially with respect to the movable carrier C. Each link is connected at its inner end to a corner of 55 the carrier by means of a bolt d , whereas the outer end of the link is connected to one member A by a bolt d' , said bolt d' serving as a support for pulley g on member A. It will be seen that on the downward movement of member C the links D will be forced downwardly so as to draw upon the upper ends of pivoted members A and thus swing them outwardly to their open positions, as shown in Fig. 1, but on 60 65 the upward movement of member C within

frame B the links D will be pulled upon so as to force outwardly the upper ends of pivoted members A, thereby swinging said members on the bolts f and moving them to their closed positions as shown in Fig. 2. 70 In this connection it is desired to call attention to the fact that the toggle links D are not straightened between the centers d d' when the members A are fully closed, as will be seen by reference to Fig. 2, and 75 the vertical movement of part or carrier C thus acts upon the links of the toggle mechanism to impart increased force to the toggle as members A swing to their closed positions, whereby the pivoted members are 80 actuated by a toggle of increasing force so as to fully close the structure upon the load in a manner to seize or grapple the load notwithstanding the resistance of said load to the closing movement of the structure. 85

The upper member b^3 of the head or frame is provided with bearings for the reception of pulley shafts i , one of which is provided with a pulley I, and the other 90 with a pulley I'. The hoist line E passes downwardly through the top part b^3 of the head or frame so as to engage with pulley I', thence said hoist line passes to and beneath pulley H of the moving part or 95 carrier C, and thence passes in an upward direction to the upper part b^3 , at which point the hoist line is anchored by a bolt e securely fastened to top member b^3 of the head or frame. 100

The dump line F passes downwardly through the top member b^3 of the frame or head in a manner to engage with the pulley I, thence said dump line passes beneath a pulley g on one of the pivoted members, thence said line passes across from said pulley on one member to and beneath the other pulley g on the opposite member, and thence said dump line passes across in an opposite direction back to the first pivoted 105 member, at which point the free end of the dump line is anchored or attached by a bolt f^3 , the manner of reeving dump line F being illustrated more particularly in Fig. 2. 110

When the weight of the grapple is imposed on the dump line F the members A are opened or spread as shown in Fig. 1, the carrier C and pulley H moving downwardly to the lower part of the head or frame, whereas the links D assume substantially 115 vertical positions shown in the drawings. The members of the grapple having been opened, it is lowered into contact with the rock, boulder, or other load, and tension is applied to the hoist line E, the pull of 120 which raises the member C and pulley H within the head or frame B. The upward movement of carrier C draws on links D, the effect of which is to impart movement 125 to pivoted members A, thereby drawing the 130

lower ends of members A inwardly toward each other, whereby the links of the toggle are moved in a manner to exert increasing force upon members A as the latter are moved toward their closed positions.

The invention when embodied in a clam shell bucket, as shown in Figs. 6 to 9, inclusive, consists of pivoted members A', a skeleton frame or head B', a vertically moving part C' in the form of slides, links D', a hoist line E', and a dump line F'.

The sections or members A' composing the two halves of the clam shell bucket each consist of side plates *j* and a curved bottom *j*' provided with a cutting edge *j*², said sections being similar to devices ordinary in the art. The bucket sections are provided with upwardly extending arms *j*³, and on one side of the bucket direction pulleys J J' are supported on these upwardly extending arms *j*³ by suitable spindles *j*⁴.

The frame or head B' is shown as consisting of parallel side plates *k* substantially triangular in shape. These plates are joined or united together in a substantial manner by metallic rods *k*', and by a top plate K, the rods *k*' passing through the respective side plates of the frame or head and through the side plates *j* of the bucket sections, whereby said sections A' are pivotally supported or connected to the frame or head B'. It will be noted that the cross rods *k*' pass through the respective bucket sections A' intermediate the ends thereof, the arms *j*³ of the bucket sections extending upwardly from the pivotal rods *k*'.

The top cross piece K of the frame or head B' is provided with a central slot *l*, and adjacent to this slot is a road bracket L' which supports the arbor *l*² of a direction pulley L, the latter being positioned at one side of the slot *l*. The hoist line E' passes downwardly through the slot *l* to and beneath a pulley M which is mounted for free rotation on a vertically movable member O, the latter being the equivalent, mechanically considered, of the carrier C in the construction of the grapple shown by Figs. 1 to 5, inclusive, said hoist line E' passing from the pulley M upwardly to a lug *e*² provided on the under side of the top cross plate K, whereby the free end of the hoist line is anchored on the head or frame B'.

The dump line F' passes beneath direction pulley L, thence across the upper part of the bucket, as shown in Fig. 8 to and over a pulley L', the latter being supported at the upper corner of the bucket exteriorly to the pivoted sections thereof, thence the dump line passes downwardly around the pulley J' supported on the arm *j*³ of one bucket member A', thence across the bucket to and around the pulley J supported

on the arm *j*³ of the other bucket section, and thence back across the bucket toward the pulley J', the free end of said dump line F' being anchored fixedly on the bucket in a suitable way at *f*⁵, 70 see the dotted line illustration in Figs. 6 and 7. It should be stated that a direction sheave M' is supported in a hanger depending from the top cross member K so that the hoist line E' will contact with said sheave M' as it runs toward the pulley M. Furthermore, a direction sheave L' is supported on the outside of the bucket between the direction pulley L' and the pulley J', the pulleys L L' and L' being so 80 related that the dump line F' will be properly directed toward the pulleys J J' on the respective bucket sections.

The side plates *k* of the head or frames B' are provided with vertical guideways *p* and with slots *p*', said guideways being reduced in width at their lower parts so as to form shoulders *p*², as shown more particularly in Fig. 9. The guideways *p* and slots *p*' open through the lower edges of plates *k*. 90 In each guideway is fitted a slide C', the upper part of which is headed at *q* so as to form shoulders *q*'. The slide fits within the guideway for the headed upper part *q* to occupy the wide part of the guideway *p*, 95 but when the slide reaches a certain point in its downward movement the shoulder *q*' of said slide rests upon the shoulder *p*² of the guideway, thereby limiting the downward movement of the slide relative to the 100 head or frame. The slides C' are provided with slots *r*, the latter being in alignment with the slots *p* in the side plates *g* of the frame. The spindle O extends horizontally across the frame or head, the end portion *o* 105 of said spindle receiving the links D', as shown in Figs. 6 and 8. Said spindle is reduced in diameter, as at *o*', to form tenons, and the tenons of said spindle pass through the slots *r* in the slides, and the slots *p*' in 110 the side plates of the frame or head. The slides *p* are retained in the guideways of plates *k* by face plates *k*⁴ suitably secured to plates *k*, and it is thus apparent that the slides are free to move up and down with 115 spindle O relative to the plates *k* of head B', although the downward movement of the slides C' will be limited by the shoulders *q*' thereof contacting with the shoulders *p*² of the side plates *k*, but the operation of 120 stopping the downward movement of the slides C' does not necessarily arrest the downward movement of the spindle O, for the reason that spindle O is free to travel in a downward direction in the slots *p*' of 125 the side plates and the slots *r* of slides C'. The slots C' thus act primarily as guides for the vertical movement of spindle O, and as the lower ends of slots *r* in the slides are closed, it is apparent that the slides will 130

serve, also, to arrest the downward movement of the spindle and its consequent disengagement from the operating parts of the bucket.

5 The links D' are positioned in pairs at the respective sides of the bucket. The links of one pair are connected pivotally to arms j^3 of the bucket sections by the bolts j^4 , whereas the inner ends of the links comprising each pair are fitted on the end portion o of spindle O . The spindle and the links form the toggle mechanism, said spindle O being the mechanical equivalent of the pulley carrier C in the construction here-
10 tofore described. The pulley M is supported on the spindle O for rotation freely thereon, said pulley being retained in position by collars s so as to prevent sliding movement on the spindle. The pulley is
15 shown as having guides s' for retaining the hoist line in proper engagement with the pulley.

By imposing the weight of the bucket upon the dump line F the stress or pull of
20 said line on the anchorage f^5 tends to move the direction sheaves $J J'$ inwardly and to depress the links D' and the spindle O , whereby the sections A' of the bucket are thrown open, as shown in Fig. 6. The
25 bucket may now be dropped into contact with the material so as to partially embed said bucket therein, and tension is applied to the hoist line E' . The pull of the hoist line on the fixed anchorage e^2 tends to raise
30 pulley M and spindle O , said spindle moving upwardly in the slot r until it contacts with the upper closed ends of said slots in the slides C' , and thereafter the continued upward movement of the spindle and the
35 pulley lifts the slides C' in the guideways p , whereby the spindle is directed by the coöperating slides and guideways of the head or frame. This upward movement of the spindle tends to elevate the inner ends
40 of the links D' and to swing the bucket sections A' on their pivots k' , thereby closing the bucket sections toward each other. It is to be noted that the links of the toggle
45 move toward a position wherein the toggle links will be in alinement during the inward or closing movement of the bucket sections, and this toggle mechanism has its parts so proportioned and arranged that said toggle mechanism acts with increasing force during
50 the closing movement of the bucket, thus loading the bucket efficiently notwithstanding the resistance of the material composing the load. The bucket with its load may be hoisted and conveyed by the line E' to a
55 place where the load is to be dumped, at which time the weight of the bucket and load is shifted from line E' to dump line F' , whereby the pull of line F' from the fixed anchorage f' draws the pulleys $J J'$
60 toward each other, thereby swinging sec-

tions A' of the bucket to their open positions, thus automatically discharging the load.

Having thus fully described the invention, what I claim as new, and desire to secure by Letters Patent is:—

1. In an excavator, the combination with a head or frame, of a plurality of members pivoted to said head or frame, a vertically movable member, links connecting said pivoted members with said vertically movable member, a hoist line coöperating with said vertically movable member for imparting movement thereto in a direction to close said pivoted members, said links and the vertically movable member operating to increasingly apply force upon the pivoted members as the latter move inwardly toward each other, and a dump line having running engagement directly with said pivoted members for imparting movement thereto in an outward direction.

2. In an excavator, the combination with a head or frame, of a plurality of members pivoted to said head or frame, a sliding part, means for directing the movement of said sliding part relatively to said head or frame, links connecting said sliding part with the pivoted members, a hoist line for imparting movement in one direction to said sliding part, said links and the sliding part forming a toggle mechanism operated by the hoist line for exerting force increasingly upon the pivoted members as the latter swing inwardly toward each other, and a dump line having running engagement with said pivoted members for imparting movement so as to swing them in an outward direction, said running engagement between the dump line and the pivoted members being positioned above the pivotal points of said members.

3. In an excavator, the combination with a head or frame, of a plurality of members each pivoted intermediate the ends thereof to said head or frame, a sliding part linked to said pivoted members, a hoist line for imparting movement to said sliding part, thereby operating to swing the pivoted members inwardly toward each other, and a dump line having running engagement with said pivoted members above the pivot thereof, said dump line operating directly upon the pivoted members for swinging them outwardly into an open position.

4. In an excavator, the combination of a plurality of pivoted members, a sliding part linked to said members, a hoist line contacting with said sliding part for imparting movement thereto in a direction for swinging the pivoted members inwardly toward each other, and a dump line having running engagement with said pivoted members for imparting movement thereto in an outward direction to open the same.

5. In an excavator, the combination of a head or frame, a plurality of members each pivoted intermediate the ends thereof directly to a rigid part of said frame, a sliding part linked to the pivoted members, a hoisting line attached at one end to the head or frame and having a running connection with the sliding part for imparting movement to the sliding part and the links so 55 as to act with increasing force upon the pivoted members during the closing movement thereof, and a dump line having a running connection with said pivoted members for positively opening the latter.
- 10 6. In an excavator, the combination of a head or frame, a sliding part movable therein, a plurality of pivoted members each having a direct pivotal connection with a rigid part of said head or frame, links pivoted to the sliding part and to said pivoted members, a hoist line, and a dump line attached to a part of the structure and having a running connection directly with the pivoted members.
- 15 7. In an excavator, the combination of a head or frame, a sliding part movable therein, a plurality of pivoted members each having a direct pivotal connection with a rigid part of said head or frame, links pivoted to the sliding part and to said pivoted members, a hoist line attached to the head or frame and having a running engagement with the sliding part, and a separate dump line having a running engagement directly 20 with the pivoted members.
- 25 8. In an excavator, the combination of a head or frame, a pulley carrier slidably fitted thereto, a pulley mounted in said carrier, a hoist line attached at one end to said frame and having a running engagement 40 with the pulley of said pulley carrier, a plurality of members each having a direct pivotal connection with the rigid part of said frame, and links pivoted to the pulley carrier and to the pivoted members.
- 30 9. In an excavator, the combination of a head or frame provided with a vertical guideway, a pulley carrier fitted to said guideway for vertical movement relative to 45 the head or frame, a pulley journaled on said carrier, a hoist line attached to the frame and having a running engagement with the pulley, a plurality of members each having a direct pivotal connection with a rigid part of said frame or head, and links pivoted to the pulley carrier and pivoted to the pivoted members.
- 35 10. In an excavator, the combination of a head or frame, a sliding part therein, a plurality of members each pivoted directly to a rigid part of said head or frame, certain of said pivoted members being provided with pulleys, links pivoted to the sliding part and to the pivoted members, a dump line attached at one end and having 55 a running engagement with the pulleys of said pivoted members, and a hoist line having a running engagement with said sliding part.
- 40 11. In an excavator, the combination with 70 a frame, and a plurality of swinging members pivoted thereto, of a sliding part operatively connected with said swinging members, guiding means with which said sliding part is in contact, a hoist line coöperating 75 with said sliding part for imparting movement thereto and thereby move the swinging members in one direction, and a dump line reeved into sliding engagement with the swinging members for directly imparting 80 movement thereto in an opposite direction.
- 45 12. In an excavator, the combination with 85 a frame, and a plurality of swinging members pivoted thereto, of a sliding part, guiding means in contact with said sliding part 90 for directing the movement thereof, means connecting said sliding part with the swinging members, a hoist line attached to the frame and having running engagement with the sliding part, and a dump line separate 95 from the hoist line, said dump line having sliding engagement with said swinging members at one side of the pivotal connections between the frame and said swinging members.

In testimony whereof I have signed my name to this specification in the presence of two subscribing witnesses.

CHARLES A. MORRIS.
